UNITED STATES PATENT OFFICE.

HENRY D. PERKY, OF GLENCOE, MARYLAND; LABAN SPARKS, ADMINISTRATOR OF SAID HENRY D. PERKY, DECEASED, ASSIGNOR, BY MESNE ASSIGNMENTS, TO THE SHREDDED WHEAT COMPANY, OF NIAGARA FALLS, NEW YORK.

MACHINE FOR MANUFACTURING GRAIN INTO FORM FOR FOOD.

1,145,918.

Specification of Letters Patent. Patented July 13, 1915.

Application filed April 2, 1906. Serial No. 309,277.

To all whom it may concern:

Be it known that I, HENRY D. PERKY, a citizen of the United States, and resident of Glencoe, in the county of Baltimore and 5 State of Maryland, have made a certain new and useful Invention in Machines for Manufacturing Grain into Form for Food; and I declare the following to be a full, clear, and exact description of the same, such as 10 will enable others skilled in the art to which it appertains to make and use the invention, reference being had to the accompanying drawings, and to letters or figures of reference marked thereon, which form a part of 15 this specification.

Figure 1 is a vertical longitudinal sectional view. Fig. 2 is a transverse sectional view. Fig. 3 is a top view. Fig. 4 is an enlarged partial longitudinal section. Fig. 6 20 represents details of the perforated pan. Fig. 7 is a sectional view of the differential pulley.

The object of the invention is to provide means for reducing cooked grain to short 25 uniform lengths of attenuated form and rough or crenated exterior, separate from each other, crisp and tender in structure, and agreeable in appearance as a breakfast food.

In the accompanying drawings, the letter *a*, designates a press; *b*, a cylindric press casing or receptacle open at both ends, which is designed to be placed in the seat *d*, of the press frame, and is removable therefrom. In axial line with the seat *d*, is the follower *e*, of the press, which is designed to be actuated by means of a screw *f*, in connection with operative gearing having a quick movement of reversal. As illustrated, 30 the follower is below the seat *d*, and is so arranged that the cylinder can be readily placed in said seat and removed therefrom. Axially above the cylinder is located an opening or mouth *w*, of rectangular shape, 35 or having parallel margins *6*. This mouth is designed to be smaller than the openings of the press cylinder, and is formed with an upward sloping throat wall *7*, having its lower opening provided with a seat *8*, designed to be engaged by the upper edge of 40 the press cylinder. The parallel edges *6*, of the mouth extend transversely of the frame, which is provided with extensions in front and in rear thereof as indicated for tables

or endless carriers *9*, flush with said mouth. 55 The frame is provided with suitable means for forcibly moving a perforated plate carrier in its plane across the press mouth *w*, in the direction of the length of the frame, and at right angles to the edges *6*, of said 60 mouth, which is designed to keep the length of the product uniform, and is the chief factor in governing such length.

The perforated or wire cloth plate *g*, in the drawing, forms the bottom or base of 65 the carrier or pan *h*, which is designed to be guided in its movement along the frame by suitable ways. The perforated plate is preferably made of sheet tin, or, it may be made of plate steel with thin edge perforations, so that it will not form a smooth, 70 round product, but will allow the material to pass in crenated or rough form depending on the movement of the material in the cylinder, and on the movement of the carrier. 75

The reduced or ground grain deprived of the hull or outer coat is placed in a closed receptacle or in a cylinder *b*, closed with air-tight caps. The material is cooked by 80 immersion in boiling water, or in a steam chamber for a suitable time, in the case of ground corn, about seven hours, the amount of water being about equal to that of the grain material with which it is mixed, or 85 such that it will be absorbed by the material, and result in a semi-solid or hardened mass. When it is cool, the cylinder charged with the material in this cooked form is placed in the press, the operation of which by suitable mechanism, not only actuates the follower *e*, but also moves the perforated carrier across the press mouth. As the follower moves slowly upward in the cylinder, the 90 perforated carrier also moves slowly across the press mouth, and the material pressed through the moving perforations is formed by continuous accretion into upright lengths or sprays, having a rounded and crenated or 95 rough exterior and substantially uniform 100 length.

The pans or carriers are designed to fit together closely end to end, and a number of them are employed in connection with the machine, which, when the carriers are fed 105 to the press in succession, and in closed end-wise relation, can be operated in a continuous manner. For this purpose, the carriers

- are placed in engagement on a feeding belt or chain device mounted on the frame extension, as indicated at 10. In a similar way, the carriers may be moved from the press 5 mouth, as they become charged with the formed sprays, on a belt device in their transition to an oven or drier. The consistency of the material in the cylinder is designed to be such that the sprays will remain in vertical position on the perforated bottom of the carrier, and, being held in such position by their terminal attachment to the perforations, will maintain each its 10 separate position. In this way, it is designed, not only to prevent the sprays from adhering to each other in bunches, but also to facilitate the access of warm air to all parts thereof to quickly and uniformly dry the product.
- 15 20 In order to facilitate the passage of the perforated carrier plate across the press mouth, where the pressure of the material tends to force the plate away from its bearing on the edges of said mouth and produce 25 a loose joint through which the material may waste, means are provided as follows: In order to loosen up the material just before it engages the perforations of the plate, horizontal ribs *k*, extending across the throat 30 or passage to said mouth just below the plane of its edges are located in said throat or passage. These ribs not only serve to lessen the pressure on the perforated plate, but they also assist in working the material 35 to homogeneous character at this point, and in causing its constituent particles to move easily with relation to each other, so that it will pass readily through the perforations. And a close joint is provided between the 40 bottom of the carrier plate and the marginal portion of the press mouth by means of the gear wheels 12, which are actuated by the driving mechanism to move the carrier, and by the loose pressure wheels 13, which 45 engage ribs 14, of the carrier as it comes into position to pass the press mouth and receive its charges. These ribs serve to strengthen the perforated plate, and to distribute the pressure over its surface. When 50 the perforated plate employed is made of

plate steel and has its perforations bordered with thin edges, the ribs are not required and the pressure wheels may engage the surface of the plate between the rows of perforations. These perforations are usually 55 made about one-sixteenth of an inch in diameter, to produce sprays of less than an inch in length. The distance between the limiting edges 6, of the press mouth may be about an inch and a quarter. The rate of 60 motion of the perforated carrier may be adjusted to suit that of the press follower by means of an adjustable differential pulley device 15, between the power shaft and the trains of gearing 16, and 17, for respectively 65 operating the press follower and moving the perforated carrier across the press mouth.

While the main factor affecting the uniformity of the length of the sprays formed on the perforated carrier plate is the press 70 mouth, it will be observed that the section or separation of these sprays at their terminals is effected by the moving plate operating against the distal edge 6, of the press mouth. And that the relative speed of the 75 traveling perforated plate, and of the feed of the material thereto, has an important bearing on the length of the sprays.

What I claim as my invention and desire 80 to secure by Letters Patent is—

In a machine for making food filaments, a press seat, a press mouth portion vertically opposite said seat, a device in connection with said mouth portion to facilitate the feed, a series of separable perforated filament-carrying plates movable over and in contact with said press mouth portion, a removable open-end press cylinder engaging 85 said seat and said mouth portion, a screw-operated follower, differential means governing the relative movements of the plates and the follower, and shifting gear for 90 quick reversal of the follower.

In testimony whereof I affix my signature, in presence of two witnesses.

HENRY D. PERKY.
